Primary Examiner—Nelson C. Holtje**[57] CLAIM**

The ornamental design for a watch, as shown.

DESCRIPTION

FIG. 1 is a front elevational view of a watch showing my new design, the broken line showings of straps being environmental only and forming no part of the claimed design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view of a second embodiment of my new design of FIGS. 1-6;

FIG. 8 is a right side elevational view thereof;

FIG. 9 is a left side elevational view thereof; and,

FIG. 10 is a top plan view thereof, the bottom plan view being a mirror image.

The rear of the second embodiment is identical to FIG. 2.
